ADJUSTABLE CHOKE

Warren R. Wheeler, San Francisco, Calif.

Application November 9, 1953, Serial No. 390,813

1 Claim. (Cl. 42—79)

This invention relates to an adjustment device for a variable choke on a shotgun.

Adjustable chokes are well-known for use on shotguns, enabling a hunter to adjust the pattern of the shot to suit the range and conditions under which the hunter is shooting. In other words, an adjustable choke allows the hunter to select an optimum shot pattern and maintain the size of pattern at various ranges.

In the past, such devices have required that the hunter turn an adjustment on the barrel end of the shotgun. This is undesirable for reasons of both safety and convenience. When it is necessary to make an adjustment in the barrel end of the shotgun, there is always a hazard since the gun barrel must be pointed at or near the hunter, endangering the life of the hunter and others who may be hunting with him. It is also inconvenient to adjust the choke in this manner since it is impossible to make the adjustment while the gun is being pointed in the vicinity of a prospective target. For example, if the gun is set for long range shooting and a bird is flushed near the hunter, there is not sufficient time to adjust the pattern for the close range and a bird would, as a result, be either mutilated or missed altogether.

It is therefore an object of the present invention to provide an adjustment for a variable choke on a shotgun or the like wherein the adjustment can be made by a hunter while the gun is in or near the normal shooting position.

Another object of this invention is to provide an adjustment for a choke which is simple, inexpensive to manufacture and substantially foolproof in operation.

Referring now to the drawings:

Figure 1 is a side elevation of a gun having mounted thereon the device of the present invention, said drawing being partially in section.

Figure 2 is a sectional view on the line 2—2 of Figure 1.

Figure 3 is a sectional view on the lines 3—3 of Figure 1.

Referring now to the drawings by reference characters, there is shown a shotgun having a barrel 5 and a magazine tube 7. Mounted on the barrel 5 is a choke generally indicated at 9. Such chokes are well-known to those skilled in the art and will not be described in detail. However, the choke has an inner portion 11 which has a series of splines 13 therein. The second portion of the choke 14 slides within the member 17 and has a wedge-shaped abutment 19 thereon, which abuts against the member 11, as illustrated. Thus, as the member 15 is

2

slid toward the rear of the gun, the splines 13 are pushed inwardly, exerting the choking action, while the bore is fully open when member 15 is in its forward position.

According to the present invention, the inner member 15 has connected thereto an arm 21 which slides in the slot 23 of the member 17. A rod 25 is connected to the arm 21, as shown, and the rear end of the rod 25 terminates in a slender portion 27 having an enlarged head 29 thereon. The portion 27 slides through a retainer 31, which also serves as a holder for the spring 33. The spring 33 is a compression type spring which is compressed as the rod 25 moves toward the front of the gun. Therefore, the spring 33 tends to keep the rod 25 biased toward the rear of the gun. Mounted on the barrel of the gun 5 is a clamp 35 which has a shaft 37 running therethrough. At the center of the shaft is a cam 39 and the head 29 of the rod 25 bears against the cam 39, as is shown. The shaft 37 also has a handle 41 thereon for turning the cam. If desired, the cam 39 can have a series of flat faces, providing a detent action. Also, the fit of the shaft 37 in the clamp 35 can be made snug, so that the cam is held in the desired place by friction.

To operate the choke, it is only necessary to set the handle 41 at a desired position. For instance, in Figure 1 two alternate positions, designated 41A and 41B, are shown in dotted lines. Therefore, the hunter may set the choke to any desired position by merely turning the lever 41 and, as is apparent, this may be done while the gun is still in substantially the shooting position. Thus, there has been provided a device for operating the choke which is operable from the rear of the gun, and which is much faster and safer to use than a conventional choke adjusting mechanism.

I claim:

In an adjustable choke for a shotgun having a movable sliding member located on the muzzle end of the barrel of the shotgun and a rod connected to said sliding member extending toward the rear of the gun whereby movement of said rod serves to adjust the choke, the improvement comprising a clamp on the barrel of the gun, said clamp having an opening parallel to the axis of the barrel of the gun for receiving the terminal end of said rod, said clamp having two parallel side members, an opening at right angles to the barrel through said side members for pivotably receiving a shaft, a cam on said shaft between the side members having a series of flat faces thereon, a spring in said clamp urging the terminal end of said rod into contact with the flat faces of the cam and a handle on said shaft located externally of said clamp whereby said handle can be turned to bring successive flat faces of the cam into contact with the terminal end of said rod whereby turning said handle brings the rod into different positions, altering the adjustment of the adjustable choke.
